COMBINED MULTILIGHT INCANDESCENT LAMP AND SWITCH

Alfred F. Bahlke, Scotch Plains, N. J., assignor to Utility Electric Corp., Newark, N. J., a corporation of New Jersey

Application September 26, 1939, Serial No. 296,531

11 Claims. (Cl. 176—27)

Many incandescent electric lamps today are manufactured with a plurality of filaments of different wattages related and combined with each other so that they may be placed in the electric circuit either separately or all together so as to secure at will illumination of varying degrees of intensity. The invention relates particularly to "multilight" lamps wherein each filament has the same characteristics as that of an ordinary one filament lamp of the same wattage, as distinguished from the old so-called "turn-down" lamps having two filaments so related that when they are connected in series one will glow while when one is short-circuited the other will glow.

My invention contemplates particularly a multilight lamp wherein the filaments can be energized in succession individually and together by rotation continuously in one direction of a switch operating element that constitutes a part of the lamp.

One object of my invention is to provide a combination electric incandescent lamp and switch which shall include the usual or standard lamp base, and a novel and improved combination of one or more contact members mounted on said base, at least one of which is connected to one terminal of a filament, and a switch operating ring rotatably mounted on the base coaxially therewith and carrying a contact element to cooperate with said contact members to selectively connect and disconnect said filament in and from an electric circuit, respectively.

Another object is to provide a combination electric lamp and switch of this character which shall include a plurality of filaments, and wherein contact members on the lamp base cooperate with a contact element on said switch operating ring to cause selectively energization of said filaments individually or one at a time, and all at one time, and deenergization of all of the filaments.

A further object is to provide a switch operating ring which shall embody novel and improved features of construction whereby it can be easily and quickly applied to a lamp base in overlying relation to said contact members.

Another object is to provide a combination of contact members and a switch operating ring as described, which shall be constructed and combined in a novel and improved manner, whereby they shall cooperate to permit rotation of said operating ring in only one direction and thereby ensure energization and deenergization

of the plurality of filaments in predetermined succession.

Other objects are to provide a switch operating ring which shall include a plurality of complementary sector-shaped sections applicable to the lamp base in a plane normal to the axis of the base, and novel and improved means for connecting said sections together in surrounding relation to said lamp base; and to obtain other advantages and results as will be brought out by the following description when read in conjunction with the accompanying drawings in which—

Figure 1 is a side elevational view of a combination multi-filament incandescent lamp and switch embodying my invention.

Figure 2 is a bottom plan view.

Figure 3 is a horizontal sectional view taken on the line 3—3 of Figure 1, drawn on an enlarged scale.

Figure 4 is a fragmentary side elevational view of the base of the lamp with the switch operating ring removed.

Figure 5 is a view similar to Figure 2 showing the manner of assembling the sections of the switch operating ring on the lamp base.

Figure 6 is an enlarged fragmentary horizontal sectional view of the switch operating ring detached from the lamp base, and illustrating the manner of connecting the two sections of the ring together.

Figure 7 is a view similar to Figure 2 with portions broken away and shown in section, illustrating a modification of the invention.

Figure 8 is a view similar to Figure 5 showing the manner of assembling the sections of the switch operating ring shown in Figure 7.

Figure 9 is a vertical sectional view on the line 9—9 of Figure 7, and

Figures 10 to 14 inclusive are schematic views showing the operations of the switch for controlling the circuits through the filaments of the lamp.

Specifically describing the invention, the reference character A designates the usual glass bulb or envelope of an incandescent lamp within which is mounted a plurality of filaments B and C which have a common terminal D and individual terminals E and F respectively. Generally, the two filaments B and C are of different wattage, and in accordance with the invention are energized either individually or together as may be desired.

The lamp also includes a base G which is of generally known standard construction including an outer screw threaded conducting shell termi-

nal 1 to be screwed into an electric lamp socket, and a central terminal 2. The common terminal D of the filaments B and C is permanently connected to one of the terminals of the base, in the present instance the central terminal 2. In accordance with the invention, a switch for controlling the circuits through the filaments B and C is mounted on the base G, preferably exteriorly thereof.

10 As shown, a band 3 of insulating material is secured exteriorly of the shell 1 adjacent the bulb A. A pair of contact members 4 and 5 for the respective terminals E and F of the filaments B and C, are secured in this insulating band and project from the circumference thereof. Each contact member is in the form of a spring strip secured at one end to the band 3 by a rivet 6, the contact members being insulated from the shell by the band, and by openings 7 in the shell which provide a clearance between the shell and the rivets. Preferably the filament B is a 20 watt filament, while the filament C is a 40 watt filament, and the contact member 4 is connected to the terminal E of the 20 watt filament, while the other contact member 5 is connected to the terminal F of the 40 watt filament.

Another contact member 8, similar to the contact members 4 and 5, is electrically connected to the shell 1 by a rivet 9.

30 The contacts 4, 5 and 8 are spaced circumferentially of the insulating band 3 in approximately a common plane that is normal to the axis of the shell terminal or lamp base, the free ends of the spring strips of the contact members projecting in the same direction circumferentially of the insulating band.

The various contact members cooperate with a switch operating member that is in the form of a sectional ring H of insulating material and is rotatably mounted on the base G coaxially therewith and in overlying relation to the contact members. Preferably the ring is formed of a plurality of approximately sector-shaped complementary sections 10 that are applied to the base exteriorly thereof in the general plane normal to the axis of the base. As shown in Figures 1 to 5 inclusive, there are two approximately semi-circular sections that are identical in construction.

50 In accordance with the invention, the sections are so constructed that they may be easily and quickly and permanently applied to the lamp base without the use of fastener elements such as rivets or screws. As shown, each section has an arm 11 projecting from one end thereof and a groove 12 at the other end to receive the arm 11 of the other section. The arms and slots are disposed approximately chordally to the exterior perimeter and tangentially to the interior perimeter, and each arm has a lug with a shoulder 13 to engage a correspondingly shaped shoulder 14 in the groove of the other section. The arms 11 are preferably formed of somewhat resilient material, and in assembling the two sections, the arm of each section is slid longitudinally into the slot of the other section, either longitudinally of the arms or laterally thereof, until the shoulder 13 of one section abuts the shoulder 14 of the other section, as shown in Figure 3. Figures 5 and 6 illustrate the connection of the sections by sliding of the arms longitudinally, Figure 6 showing the relation of the parts just prior to the engagement of the shoulders 13 and 14. To prevent relative movement of the two sections laterally of the arms or along the axial plane in

which the abutting ends of the sections lie, the end of one section may have a protuberance 15 to snap into a recess 17 in the juxtaposed end of the other section approximately simultaneously with the engagement of the shoulders 13 and 14, as shown in Figures 6 and 2.

The interior surface of the ring H has a circumferential groove 18 which is of a width and depth to freely receive the insulating band 3 as shown in Figures 3 and 9 so that said band serves as a guide for rotation of the ring H and holds the latter against axial movement longitudinally of the base.

At the base of the groove 18 is a narrower groove 19 in which is seated a segmental conductor or contact element 20 that is preferably in the form of a round wire. For securing this conductor in position to rotate with the ring H, one end of the conductor wire may be bent outwardly as at 21 and seated in a socket 22 in one of the sections 10 of the ring H. The length of the conductor 20 is such that it may electrically connect all of the contacts 4, 5 and 8 in one position or electrically connect only two of the contact members in other positions. The contact strips are of resilient nature so as to constantly maintain spring frictional contact with the base of the groove 18 or the conductor 20. Also, the contact members are preferably of a width to loosely enter the groove 18 of the ring H so that the contact members are housed between the ring H and the insulating band 3.

In operation, referring to Figure 10 of the drawings, the ring H is so positioned that the conductor 20 engages the two contacts 4 and 8 whereby only the filament B is energized. In Figure 11 the ring H has been moved in the direction of the arrow so that only the two contacts 5 and 8 are connected by the conductor 20 so as to energize only the filament C, while Figure 12 shows the conductor 20 engaging all three contacts 4, 5 and 8 so as to energize both of the filaments. Figure 14 shows the conductor 20 engaging only the contacts 4, 5 so that the circuit is completely broken and both filaments are de- energized.

In order to permit the switch operating ring H to rotate in only one direction and thus insure energization and deenergization of the filaments in the desired succession, the sections 10 of the ring H may have teeth or lugs 23 formed integrally therewith projecting upwardly from the bottom of the grooves 18, and provided with radial faces or shoulders 24 to abut the ends of the contact members 4, 5 and 8, and inclined top surfaces 25 to permit the lugs or teeth to slide freely over the contact members upon rotation of the ring H in one direction, as shown by the arrows in the various figures. The lugs or teeth 23 are so circumferentially spaced that at least one thereof will engage one of the contact members 4, 5 or 8 in each of the circuit controlling positions of the ring H above described and as particularly shown in Figures 3 and 10 to 14 inclusive. It will thus be seen that the contact members in effect constitute spring pawls co-operating with ratchet teeth 23 to permit rotation of the ring H in only one direction.

Also, it will be observed as shown in Figure 13, that the teeth 23 raise the contact members from the conductor 20 as the operating ring is moved to make the circuit changes, so that the circuit is closed each time with a snap action as the contact members are released by the teeth.

A modification of the switch operating ring is

shown in Figures 7 and 8 where the ring I comprises two approximately semi-circular sections 26 and 27 one of which has a spring arm 28 at one end and another spring arm 29 at the other end. Each arm has a lug 30 to cooperate with a shoulder 31 in a groove 32 in the outer surface of one end of the other section.

In connecting the two sections, the lug 30 of the arm 29 is first engaged with one of the shoulders 31 of the other section, after which the first mentioned section is moved with a hinged action to cause the arm 28 and its lug 30 to snap over the shoulder 31 at the other end of the second mentioned section, as shown in Figure 8. With this construction, the two arms 28 and 29 hold the sections against lateral movement in all directions because the arms of one section embrace the corresponding ends of the other section, and thereby avoid the necessity for means such as the lugs 16 and recesses 17 of the structure shown in Figures 1 to 6 inclusive.

The structure of the switch operating ring I shown in Figures 7 and 8 may otherwise be identical with that of the ring H shown in Figures 1 to 6 inclusive.

In this connection, it should be understood that if the sections 10 of the operating ring H are made so as to provide a clearance between the inner periphery of the ring and the lamp base less than the depth of the shoulders 13 and 14, the lamp base would prevent such relative lateral movement of the sections as might disengage the shoulders 13 and 14, and thereby the necessity for the lugs 16 and recesses 17 could be avoided. Practically, however, it is desirable to have the shoulders 13 and 14 as shallow as possible and also provide substantial clearance between the operating ring H and the lamp base so that the lugs 16 and recesses 17 or their equivalents are preferred.

In addition to the advantages incident to the plurality of filaments, it will be understood that my combined lamp and switch can be used in an electric socket that does not have a switch, the switch of my structure being capable of performing the functions of the usual socket switch.

Obviously the details of structure of the lamp and switch, the number of filaments, the number and arrangement of the switch contact members, the length of the conductor element, the number of sections of the switch operating rings, and the manner of connecting said sections, may be widely modified and changed by those skilled in the art without departing from the spirit or scope of the invention.

Having thus described my invention, what I claim is:

1. A combined electric incandescent lamp and switch, comprising a base having a shell terminal and a central terminal, a bulb, a filament in said bulb, means for energizing said filament including a direct electrical connection between one terminal of said filament and said central terminal of the base, a plurality of contact members mounted exteriorly on said shell terminal in spaced relation circumferentially thereof, one of which is electrically insulated from said shell terminal and electrically connected to the other terminal of said filament while another contact member is electrically connected to said shell terminal, and a switch operating ring rotatable coaxially on said base exteriorly thereof and having a segmental conductor extending circumferentially of said ring to electrically connect and disconnect selectively the first-mentioned contact

member with and from the second mentioned contact member upon rotation of said switch operating ring in one direction, said switch operating ring also having ratchet teeth to directly engage said contact members and prevent rotation of said ring in the other direction.

2. The combined electric incandescent lamp and switch set forth in claim 1 wherein said contact members comprise spring strips secured at one end to said shell terminal and with their other ends extending in the direction of rotation of said switch operating ring, and said ratchet teeth have radial faces to engage the second-mentioned ends of said contact members and inclined top surfaces to ride over said contact members.

3. The combined electric incandescent lamp and switch set forth in claim 1 wherein said contact members comprise spring strips secured at one end to said shell terminal and with their other ends extending in the direction of rotation of said switch operating ring, said switch operating ring has an interior circumferential groove within which said contact members are located, said conductor is seated in the base of said groove, and said ratchet teeth are integral with said operating ring and project outwardly from the base of said groove beyond said conductor and have radial faces to engage the second-mentioned ends of said contact members and inclined top surfaces to ride over said contact members.

4. The combined electric incandescent lamp and switch set forth in claim 1 with the addition of a band of insulating material secured exteriorly and coaxially on said shell terminal, and wherein said contact members are mounted on said band and said switch operating ring has an interior circumferential groove loosely slidably receiving said band and said contact members, whereby said band serves as a guide for said switch operating ring.

5. The combined electric incandescent lamp and switch set forth in claim 1 with the addition of a band of insulating material secured exteriorly and coaxially on said shell terminal, and wherein said contact members comprise strips of spring material secured at one end to said band and with their other ends extending in the direction of rotation of said switch operating ring, said operating ring has an interior circumferential groove loosely slidably receiving said band of insulating material and said contact members, said conductor is mounted in the base of said groove, and said ratchet teeth are integral with said operating ring and project outwardly from the base of said groove beyond said conductor and have radial faces to engage the second-mentioned ends of said contact members and inclined top surfaces to ride over said contact members.

6. A combined electric incandescent lamp and switch which has a switch and an operating ring therefor rotatable exteriorly and coaxially on the base of the lamp, wherein said switch operating ring comprises a plurality of complementary sector-shaped sections applied to said base in a plane normal to the axis of the base, said sections having cooperating interlocking elements at their ends securing said sections together.

7. A combined electric incandescent lamp and switch which has a switch and an operating ring therefor rotatable exteriorly and coaxially on the base of the lamp, wherein said switch operating ring comprises a plurality of complementary sector-shaped sections applied to said base in a

- plane normal to the axis of the base, said sections having cooperating spring catch arms and shoulders at their ends for connecting said sections together.
5. 8. A combined electric incandescent lamp and switch which has a switch and an operating ring therefor rotatable exteriorly and coaxially on the base of the lamp, wherein said switch operating ring comprises a plurality of complementary 10 sector-shaped sections applied to said base in a plane normal to the axis of the base, one end of each section having a spring arm with a lug thereon and the other end having a groove with a shoulder therein, said arm of each section being fitted in said groove of the juxtaposed section with said lugs engaging said shoulders, for connecting said sections together.
9. A combined electric incandescent lamp and switch which has a switch and an operating ring 20 therefor rotatable exteriorly and coaxially on the base of the lamp, wherein said switch operating ring comprises a plurality of complementary sector-shaped sections applied to said base in a plane normal to the axis of the base, one section 25 having a spring arm at each end thereof formed with a lug, and the other section having a groove in each end formed with a shoulder, said arms of one section being fitted in the respective grooves of the other section with said lugs engaging said shoulders, for connecting said sections together.
10. In combination with a base of an electric incandescent lamp having a shell terminal and a central terminal, a plurality of contact members 30 mounted exteriorly on said shell terminal in

spaced relation circumferentially thereof, at least one of which is electrically insulated from said shell terminal while at least another contact member is electrically connected to said shell terminal, and a switch operating ring rotatable coaxially on said base exteriorly thereof and having a segmental conductor extending circumferentially of said ring to electrically connect and disconnect selectively the first-mentioned contact member with and from the second-mentioned contact member upon rotation of said switch operating ring in one direction, said switch operating ring also having ratchet teeth to directly engage said contact members and prevent rotation of said ring in the other direction.

11. In the combination set forth in claim 10, the addition of a band of insulating material secured exteriorly and coaxially on said shell terminal, and wherein said contact members comprise strips of spring material secured at one end to said band and with their other ends extending in the direction of rotation of said switch operating ring, said operating ring has an interior circumferential groove loosely slidably receiving said band of insulating material and said contact members, said conductor is mounted in the base of said groove, and said ratchet teeth are integral with said operating ring and project outwardly from the base of said groove beyond said conductor and have radial faces to engage the second-mentioned ends of said contact members and inclined top surfaces to ride over said contact members.

ALFRED F. BAHLKE. 35
